Inventor
WALTER J. RODGERS, JR.

By his Attorney, *Redding, Sheehy, O'Shea and Campbell*

UNITED STATES PATENT OFFICE.

WALTER IRVING RODGERS, JR., OF BROOKLYN, NEW YORK, ASSIGNOR TO INTERNATIONAL MOTOR COMPANY, OF NEW YORK, N. Y., A CORPORATION OF DELAWARE.

WHEEL.

Application filed December 22, 1924. Serial No. 757,308.

To all whom it may concern:

Be it known that I, WALTER IRVING RODGERS, Jr., a citizen of the United States, residing in the borough of Brooklyn, of the city of New York, in the State of New York, have invented certain new and useful Improvements in Wheels, of which the following is a specification, reference being had to the accompanying drawing, forming a

10 part hereof.

This invention has for its object to provide a wheel which shall have all the advantages of a wooden wheel of the artillery type for motor vehicles and none of the disadvantages inherent in such wheel construction. The weakest part of wooden wheels of the artillery type is the felloe in which the grain of the wood of necessity runs parallel with the side of the wheel which is subject to shrinkage or splitting with the grain with consequent loosening of the spokes. According to the present invention advantage is taken of the superior strength of wood in the direction of its grain by forming a disc wheel composed of a plurality of wooden sections wherein the grain extends radially. Such a wheel has all the advantages of a steel disc wheel with the added advantage of that greater degree of resiliency afforded by the wood. The design also lends itself to offsetting for adaptation of tires of the true balloon type. The invention will now be described more particularly with reference to the accompanying drawing illustrating a preferred embodiment thereof and in which:

Figure 1 is a view in side elevation of the wheel according to the present invention, parts being removed or broken away in the interest of clearness.

Figure 2 is a fragmentary sectional view taken in the plane indicated by the line 2—2 in Figure 1 and looking in the direction of the arrows and showing particularly the manner of securing the wooden disc portion to the hub.

In the embodiment illustrated in the drawings, the vehicle wheel is composed of a plurality of wood sections *a* of the shape generally of a segment of an annulus and having plane proximate edges *a'* which are disposed in abutting relationship when the

sections *a* are disposed about the hub. While many hub constructions may be availed of in the adaptation of a wheel according to the present invention there has been illustrated in Figure 2 a hub *b* formed outwardly thereof with a flange *b'* and a seat *b*², the blocks of wood being disposed upon the seat and clamped against the flange *b'* by means of a cooperating flange *c* formed on a sleeve *c'* which is adapted to slip over the hub to rest against the inner face of the wooden blocks *a* and maintained in clamping engagement by means of bolts or the like passing through appropriate apertures *b*³, *c*² in the respective flanges and through appropriate holes *a*² bored in the wooden blocks. Circumferentially of the series of blocks and engaging the outer marginal surfaces thereof there is disposed a rim *d* which may be shrunk thereon or secured thereto in any conventional manner. This rim may be provided with suitable apertures *d'* registering with apertures *a*³ in the block for the reception of bolts *e* serving as locking means for the demountable rim *e'* of a pneumatic tire.

Preferably the outer portions of the blocks are offset as at *a*⁴ whereby the rim engaging portion of the wheel is shifted outwardly with respect to the hub. Such a construction not only lends itself to the application of brake drums but is also advantageous in connection with the use of pneumatic tires of the true balloon type since by so offsetting the rim balloon tires may be used without the rearrangement or reconstruction of proximate elements of the vehicle.

It will thus be seen that a wooden wheel has been provided which is more resilient than steel wheels, takes advantage of the use of wood along the line of its greatest strength and permits advantage to be taken of various accessories which are fast becoming standard equipment in motor vehicles.

Various modifications may be made in the form taken by the hub and the type of tire carried with the wheel as well as the means for securing the same thereto and no limitation is intended except as indicated in the appended claim.

What I claim is:

In a vehicle wheel, in combination, a hub

formed with a flange, a plurality of wood sections arranged in juxtaposition thereabout with the grain of the sections running substantially radially thereof, the rim portions of said wood sections being of increased thickness and off-set with respect to the hub portions thereof, a sleeve formed with a flange, bolts to engage the flanges

and clamp the wood sections therebetween, and a rim shrunk on circumferentially about the wood sections to receive a demountable rim for resilient tires.

This specification signed this 17 day of December A. D. 1924.

WALTER IRVING RODGERS, JR.
